WATER SIGNAL SWITCH

Filed May 1, 1926

INVENTOR

Kenneth V. Knapp
BY *Frank C. Lichten*
ATTORNEY

UNITED STATES PATENT OFFICE.

KENNETH V. KNAPP, OF NEWARK, NEW JERSEY, ASSIGNOR TO HANOVIA CHEMICAL & MFG. CO., OF NEWARK, NEW JERSEY, A CORPORATION OF NEW JERSEY.

WATER-SIGNAL SWITCH.

Application filed May 1, 1926. Serial No. 105,933.

This invention relates to pressure controlled audible signals and more particularly to electrically actuated types.

There are certain classes of scientific, and 5 medical apparatus in which the accession of heat, internally generated or conducted thereto, is detrimental to their accurate operation or even destructive if the temperature becomes excessive and in such cases 10 it is usual to maintain a substantially uniform temperature by employing pipes supplied with cold water and so coiled or otherwise arranged as to absorb and carry away the excess heat.

15 Such devices, in order to fulfill their functions, must be constantly watched or thermos- statically calibrated by a careful and competent operator, particularly if fluctuations of heat occur to which such apparatus is 20 usually subject.

As an example may be mentioned therapeu- 25 tical lamps as used in the production of fluorescent rays, the behavior of which and likewise safety, depend upon maintaining an equable temperature.

It is therefore an object of the invention to provide an alarm or signalling device, the operation of which is automatically controlled by changes in the temperature and 30 pressure of the fluid flowing through the cooling coils.

A further feature is in the provision of a neat appearing, compact signal device, simple in its nature, adjustable to requirements 35 and effective in operation.

Other features and advantages will here- 40 after appear in the description taken in connection with the drawing, constituting a component hereof, and in which:—

Figure 1 is a plan view of an embodiment of the invention as fully assembled, the cover being omitted.

Figure 2 is a longitudinal sectional view taken on line 2—2 of Fig. 1.

Figure 3 is a diagrammatical view of the wiring, water supply and signal system.

The signalling device consists of a base plate designated by the numeral 10 dis- 50 posable in any convenient location, prefer- ably in an upright position as shown.

Fixed on the base to extend at a right angle is a shelf 11 and a longitudinal wall 12 divides the front of the base into nearly equal portions above the shelf, these elements sup- 55 porting a metal cover 13 which encloses the

structural parts in the manner of a box, its side and end wall reaching to the base.

Passing through the shelf 11 are two pipes 14 and 15, respectively inlet and outlet, the pipe 14 leading from the water cooling cir- 60 culatory system employed and the pipe 15 to wherever the water may be discharged.

These pipes extend in parallel to engage bosses on the opposite ends of a hollow casing 16 to communicate with the chamber 65 therein, the casing being supported by a block fixed on the base 10 and in open communication with a thin metallic bellows 17 of considerable area and diameter.

The bellows 17 is formed of metal having 70 a high co-efficient of elongation in the presence of heat and pressure, the walls of the bellows presenting a series of accordion-like annular undulations which permit ready and instant change in the length of the bellows 75 being extremely sensitive to internal pressure.

The bellows is sealed to the casing 16 in a leak proof manner and is provided at its outer end with a plate closure 18. 80

A pair of bosses 19 extend opposite the pipe receiving bosses and fixed therein are rods 20 having shouldered portions passing through a dielectric plate 21 to hold the same 85 in fixed relation to the casing 16.

Carried by the plate 21 are stop screws 22 to limit the outward movement or expansion of the bellows 17 and an opening 23 in the plate provides access to the head of a screw 24 passing adjustably through a non-con- 90 ducting bar 25 having on its face adjacent the bellows an elongated metal contact strip 26.

A pair of shouldered studs 27 and 28 are fixed in the plate 21, the stud 28 having a washer 30 disposed on the outer side of 95 the contact strip 26 and held by a clamp screw thereagainst.

The stud 27 is provided with a washer 29 and normally is engaged by the free end of the spring contact strip 26, the contact being 100 broken upon elongation of the bellows 17 in an obvious manner.

A battery 31 is disposed on the base 10 at the opposite side of the partition wall 12 and provided with terminal binding posts 105 32 and 33. A conductor 34 connects between the post 32 and stud or binding post 28, and a similar conductor 35 eventually engages the mating stud 27.

Disposed in the run of the conductor 35 110

is a buzzer, designated generally by the numeral 36 as an entity, being of common and well known construction.

Also in the line is a push-pull switch 37 controlling the circuit, the switch being supported by a bracket 38 connected over the buzzer frame and to the shelf 11, and having a manually actuated control knob 39 extending outward through an opening 40 in the cover plate 13 convenient of access.

If it be desired an incandescent bulb 41 may be provided in the line 35, or to a shunt thereof, thus affording a visible signal in addition to or independent of the audible signal.

In operation, a stream of water supplied from any convenient source is caused to circulate through suitable connections in the apparatus X to be cooled, thence conducted to the pipe 14 by which the water, raised in temperature, passes out of the open elbow 14' through the chamber 16, transmitting its pressure and some of its heat to the bellows 17, causing it to expand, and thence delivered outwardly to any convenient place for disposal by the pipe 15, the latter having a contracted inner end 15'.

When the bellows 17 is expanded to increase its length to such an extent as to press its free end against the point of the screw 24, the plate 25 and spring contact strip 26 is moved to break contact with the post 27, and, if the switch 37 be properly adjusted, the signals will not operate until the bellows has contracted.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:—

1. A signal device comprising a casing, a chambered body having means for circulation of water therethrough, said means provided with a restricted inlet within the

chamber, a bellows in open communication with the body chamber, a dielectric plate held rigidly at a fixed distance from said body beyond said bellows, adjustable stop screws in said plate to limit the expansion of said bellows, a pair of binding posts carried by said plate, a spring arm fixed to one of said posts and in normal engagement with the other post, a non-conducting block carried by said arm, a screw adjustable in said block to be engaged by the end of said bellows upon expansion thereof whereby said arm is disengaged from the last named post.

2. An automatic signal system embodying a detachable casing supported by an elongated base plate having a transverse shelf cooperating with a longitudinal disposed wall dividing said casing into contiguous compartments, said shelf being provided with a parallel disposed inlet and outlet pipes said pipes being provided with enlarged communicating bosses, a block carried by the base plate, a liquid casing supported by the block and communicating with said bosses, an open bellows operatively associated with said liquid casing, a pair of shouldered rods having a lower terminal boss supported by the liquid casing, a dielectric plate detachably supported on said shouldered rods, means carried by the dielectric plate for limiting movement of said bellows, a non-conducting bar having an elongated metal strip secured to said limiting means and complementary shoulder studs depending from the dielectric member and being provided with contact washers.

3. In a signal switch embodying a detachable casing provided with a base plate, a pair of spaced pipes adapted for transmission of liquid, a block secured to said base plate, a container for liquid supported by the block and communicating with said pipes, a bellows carried by said liquid casing, and means associated with said bellows for actuating the control of the signal switch.

This specification signed this 27th day of March, 1926.

KENNETH V. KNAPP.
